CLAIMThe ornamental design for an exercise apparatus, as shown
and described.**DESCRIPTION**FIG. 1 is a perspective view of an exercise apparatus
showing our new design;

FIG. 2 is a front view of the design of FIG. 1;

FIG. 3 is a back view of the design of FIG. 1;

FIG. 4 is a top view of the design of FIG. 1;

FIG. 5 is a bottom view of the design of FIG. 1;

FIG. 6 is a first side view of the design of FIG. 1;

FIG. 7 is a second side view of the design of FIG. 1; and,
FIG. 8 is a cross-sectional view taken along lines 8-8 of FIG.
7.The broken lines shown in the figures are for the purpose of
illustrating portions of the exercise apparatus, which form
no part of the claimed design.**1 Claim, 7 Drawing Sheets**| (56)	References Cited
